UNITED STATES PATENT OFFICE

2,186,492

PUMPING APPARATUS

Win W. Page, Michigan City, Ind., assignor to
 Sullivan Machinery Company, a corporation of
 Massachusetts

Application January 16, 1936, Serial No. 59,435

11 Claims. (Cl. 230—211)

My invention relates to pumping machinery, and more particularly to cooling means for pumping machinery in which heat of compression is developed during the pumping operation.

High pressure air is required for various purposes, such, for example, as the breaking down of coal and other materials by air shooting apparatus embodying cartridges filled with air at pressures of from 5,000 to 10,000 pounds per square inch, and arranged to effect a sudden release of their contained charge into the material to be fractured.

With such devices, apparatus of maximum simplicity and certainty of operation is highly necessary as a source of supply of the highly compressed air or other gaseous medium used, for commonly the compressing plant moves around the mine and to points closely adjacent to the working faces of the mine. Because of the portability and of the high pressures generated, an air-cooled apparatus is particularly desirable, for it reduces the weight and makes unnecessary the constant availability and transport of a substantial quantity of water.

It is accordingly one object of my invention to provide an improved air-cooled compressor to meet the conditions mentioned. It is another object of my invention to provide an improved cooling system for air compressors of the so-called air-cooled type. It is a further object of my invention to provide an improved cooling system for cooling the several cylinders of a compound high pressure compressor and for cooling the intercoolers between the several stages of compression. Other objects and advantages of the invention will hereinafter more fully appear.

In the accompanying drawing, in which, for purposes of illustration, one illustrative embodiment of the invention has been shown—

Fig. 1 is a view in plan, with parts removed to facilitate clarity of illustration, showing the compressor and cooling portions of a compressor plant adapted for use with air-shooting apparatus and in which the illustrative embodiment of the invention is incorporated.

Fig. 2 is a perspective view from the side, with parts broken away, and on an enlarged scale, of a portion of the structure shown in Fig. 1.

Fig. 3 is another perspective view of the opposite side of the apparatus shown in Fig. 1.

Since the present invention relates essentially to the compressor per se and to the cooling system therefor, a complete portable compressor outfit of the character which has previously been

mentioned is not shown. It is deemed unnecessary to illustrate the compressor driving motor and much of the internal mechanism of the compressor, since the particular nature of the compressor drive obviously is immaterial from the standpoint of the present invention, and since the cooling features are the important ones with respect to the compressor per se.

Now referring to the drawing, it will be observed that a plural stage—herein a four-stage—compressor is shown at 1, and that it comprises a series of air-cooled cylinders, herein a low pressure air-cooled cylinder 2, a first-intermediate air-cooled cylinder 3, a second-intermediate air-cooled cylinder 4, and a high pressure air-cooled cylinder 5. It will be observed that each of these cylinders is provided with appropriate cooling fins 6, and that the cylinder head 7 and valve chamber covers 8 of the low pressure cylinder are likewise provided with appropriate cooling fins, and that the head 9 of the first-intermediate cylinder is also provided with cooling fins. It will be observed that the low pressure cylinder 2 and the first-intermediate cylinder 3 are arranged at one side of the crank case 10 of the compressor, and that the second-intermediate and high pressure cylinders 4 and 5, respectively, are arranged at the opposite sides of the crank case, the cylinder pairs mentioned being arranged in V relation as supported by the crank case and providing a substantial angle between them. It will be noted, moreover, that an intercooler 12 is arranged to receive, through a connection 13, compressed air from the low pressure cylinder 2, and to deliver it, through a connection 14, to the inlet of the first-intermediate cylinder 3. A second intercooler 15 is provided to receive air, through a connection 16, from the discharge of the first-intermediate cylinder, and to deliver it to the inlet of the second-intermediate cylinder, through a connection 17. From the second-intermediate cylinder a connection 18 leads to a further intercooler 19, from which the air is delivered through a connection 20 to the inlet of the high-stage cylinder 5, and the air compressed by the cylinder last mentioned is delivered through a connection 21 for ultimate use. An air filter 22 delivers cleaned air through a connection 23 to the inlet of the low pressure cylinder 2.

The several intercoolers 12, 15 and 19 are arranged vertically and in a series transversely of the compressor, near one end thereof, and they are provided with a suitable housing, as of sheet metal, as shown at 25, preferably rounded to pro-

mote air flow, and, if desired, provided centrally with an air dividing and directing projection 26. Means for delivering cooling air to these cylinders is provided in the form of a blower 30, actuated in any appropriate manner, herein through a separate motor 31, and delivering, through a blast guiding passage 32, a large volume of cooling air. This fan is arranged at the end of the compressor opposite the intercoolers, and the blast is discharged longitudinally of the compressor and between the two cylinder "banks" directly in the direction of the intercooler 19. It will be noted that the intercoolers are of the coiled type, and that they are appropriately supported within the housing 5. 10. 15. 20. 25. 30. 35. 40. 45. 50. 55. 60.

It may now be observed that the air blast passing longitudinally between the cylinder "banks" after striking the intercooler 19, is divided and deflected laterally, the device 26 facilitating the division of the air blast and diminishing loss of velocity through eddying. The split masses of air pass respectively through and around the intercooler 12 and over the cooling fins carried by the first-intermediate cylinder 3 and its head 9 and by the low pressure cylinder 2, its head 7 and valve compartment covers 8, and through and around the intercooler 15 and across the cooling fins carried by the third-stage (second-intermediate) cylinder 4 and the high pressure cylinder 5. The compressor is provided with a cover 35 which may be raised about an axis extending transversely near the back wall of the casing 25, and thereby a portion of the air may be allowed to pass upwardly and out at the top of the compressor. By reason of the provision of a transverse baffle 36, a portion of the air passing over the low and first-intermediate cylinders will be caused to undergo a lateral discharge.

Now it will be evident that the intercooler 19 will be cooled by a rush of largely unwarmed air; that the air passing between the two "banks" of cylinders will be divided and pass over these after passing over, in each case, one intercooler coil; that the blast fan and the associated arrangements cause the air to pass over and cool the cylinders, largely with air flowing in a direction opposite to that in which the blast fan discharges; that each cylinder "bank" has its own definite air stream for cooling purposes; that a very large volume of air may be delivered for cooling purposes by the arrangement shown, and that exceedingly efficient temperature control during the compression may be secured by the apparatus illustrated.

While I have in this application specifically described one form which my invention may assume in practice, it will be understood that this form is shown for purposes of illustration only and that the invention may be modified and embodied in various other forms without departing from its spirit or the scope of the appended claims.

What I claim as new and desire to secure by Letters Patent is:

1. In combination, in a compressor, cylinder structures arranged in V relation, cooling means for the compressed fluid including intercoolers at one end of said compressor in the same vertical planes extending longitudinally of the compressor with said cylinder structures respectively, a cooling fan arranged at the end of said compressor opposite said intercoolers, and means for distributing substantially opposite to fan discharge the air therefrom in distinct streams to the cylinder structures and intercoolers at the opposite sides of the V.

2. In a compressor, in combination, a series of cooling coils, a series of compressor cylinders, certain of said cylinders and one of said coils being in one series of vertical planes, another of said coils and others of said cylinders in a spaced series of parallel planes, a third coil in an intermediate series of vertical planes, and means including a cooling fan and flow directing means for causing a flow of air in one direction in said last mentioned series of planes and over said third coil and in the opposite direction in said first and second mentioned series of planes and over said other coils and said cylinders. 5. 10. 15. 20. 25.

3. In a compressor, in combination, a series of cooling coils, a series of compressor cylinders, certain of said cylinders and one of said coils being in one series of vertical planes, another of said coils and others of said cylinders in a spaced series of parallel planes, a third coil in an intermediate series of vertical planes, and means for 20 delivering air first in one direction in said last mentioned series of planes and over said third coil and thereafter in divided streams reversely in each of the first and second mentioned series of planes and over the coils and cylinders therein. 25

4. In a compressor, in combination, a low pressure cylinder, a high pressure cylinder, an intercooler through which flow takes place in passing from the low pressure cylinder to the high pressure cylinder, said low and high pressure cylinders being laterally spaced and said intercooler lying intermediate but spaced longitudinally of the compressor with respect to said cylinders, means arranged at the far side of said cylinders from said intercooler for directing a flow of air over said intercooler in a unitary stream, and means adjacent said intercooler for dividing said unitary stream and directing the divided streams over said cylinders. 30. 35.

5. In a compressor, in combination, low pressure and first-intermediate cylinders, second-intermediate and high pressure cylinders, three intercoolers, one connected between each pair of consecutive cylinders, one of said intercoolers being in the same set of longitudinally extending vertical planes with the first mentioned pair of cylinders, another in the same set of vertical longitudinally extending planes with the second mentioned pair of cylinders, and the third in an intermediate series of planes, said intercoolers arranged at one end of said compressor, a cooling fan arranged at the opposite end of the compressor and discharging longitudinally of said compressor in said last mentioned series of planes and upon said third intercooler, and flow dividing and guiding means for redirecting the air reversely longitudinally of the compressor in spaced streams respectively cooling the first mentioned pair of cylinders and the intercooler in the same vertical planes therewith, and the second mentioned pair of cylinders and the intercooler in the same vertical planes with the latter. 40. 45. 50. 55. 60.

6. In combination, in an apparatus for effecting the multi-stage compression of air, a cylinder at one side of a vertical plane, a higher stage cylinder at the opposite side of said plane, associated means for cooling compressed fluid arranged at one side of a zone to which said plane is perpendicular and containing said cylinders, means for creating a stream of air arranged at 70 the other side of such zone and discharging towards said associated cooling means, and flow-directing means for reversing said air and directing it upon said cylinders, after its action on said cooling means, in separate streams moving 75

in a direction opposite said first mentioned stream.

7. In combination, a compound fluid-compressing apparatus having stages at opposite sides of a series of parallel vertical planes, intercooling means including heat exchange devices also arranged at opposite sides of said planes, and means for cooling said intercooling means and thereafter said stages including means for creating a flow of cooling fluid along said planes and means for dividing such flow and directing it first over said devices and then over said stages.

8. In combination, a compound fluid-compressing apparatus having stages at opposite sides of a series of parallel vertical planes, intercooling means also arranged at opposite sides of said planes, intercooling means in said planes, means for creating a flow of cooling fluid along said planes and over said last mentioned intercooling means, and means for thereafter dividing such flow and directing it first over said first mentioned intercooling means and then over said stages.

9. In combination, in a multi-stage compressing apparatus, means for creating a directed flow of cooling fluid, air-cooled cylinders constituting different stages of such apparatus arranged with their axes in a plane parallel to the direction of flow of such cooling fluid, an intercooler for said cylinders arranged at the far side of said cylinders from said first mentioned means and directly to receive the flow of cooling fluid, and means for reversing the flow arranged beyond said intercooler and directing the flow upon said cylinders in a path substantially the reverse in direction of the original direction of flow.

10. In combination, in a compressing appara-

tus, air-cooled cylinders arranged at opposite sides of a plane, fluid cooling means including heat exchange devices also arranged at opposite sides of such plane, and cooling means including means for creating a flow of cooling fluid along said plane between said cylinders and then dividing it and directing it across said heat exchange devices, and then, in substantially opposite directions to its direction of original flow, over said cylinders.

11. In combination, an air compressor of the air cooled type having cylinders for providing different stages of compression and arranged in laterally spaced relation to provide an open space therebetween, an intercooler having cooling elements for cooling the compressed air as it flows from one cylinder to another during the different stages of compression, and cooling means for said cylinders and said intercooler cooling elements comprising a blower discharging in a unitary stream longitudinally into said space between said cylinders along the inner sides of the latter, one of said intercooler cooling elements arranged in the path of the blower discharge and having the cooling fluid pass over it as said fluid flows through said space between said cylinders, and means against which said fluid stream impinges for dividing the fluid stream into separate cooling-fluid streams and directing the latter laterally past others of said cooling elements of said intercooler and then longitudinally in a reverse flow direction past the outer sides of said cylinders, the divided streams of cooling fluid flowing in a direction opposite to and out of the path of the blower discharge.
